UNITED STATES PATENT OFFICE.

CHRISTOPHER G. GUIGNARD, OF COLUMBIA, SOUTH CAROLINA.

DRYING OF CLAYWARE AND THE LIKE.

1,204,430.

Specification of Letters Patent. Patented Nov. 14, 1916.

Application filed February 16, 1914. Serial No. 819,011.

To all whom it may concern:

Be it known that I, CHRISTOPHER G. GUIGNARD, a citizen of the United States, residing at Columbia, in the county of 5 Richland and State of South Carolina, have invented certain new and useful Improvements in the Drying of Clayware and the like, of which the following is a specification, reference being had therein to the 10 accompanying drawing.

This invention relates to methods of and apparatus for drying clay-ware, such as brick, tile, and the like.

The primary object of the invention, in 15 one aspect, is to provide a drier of the character specified in which the heat from producer-gas is effectively utilized for drying clayware in tunnel-kilns.

The invention has further for its object 20 the effective utilization of the heat derived directly from the combustion of producer-gas projected into or drawn through mixing and combustion chambers, of special construction, and which heat thus produced 25 is subsequently distributed to conduits or radiators with a minimum loss of heat-units and with a maximum degree of efficiency. The heat radiating from the radiators is used to effect drying in adjacent tunnels.

30 The invention has also for its object the provision of appropriate apparatus structurally and functionally adapted to produce novel results and with relative economy in its operation. The apparatus, from an 35 operative standpoint, will, in practical use, possess a high degree of efficiency and, from a structural standpoint, is of the greatest possible simplicity.

Other objects and advantages will in part 40 be obvious from the annexed drawings and, in part, will be pointed out in the following description.

With these and other objects in view, the invention resides broadly in the features of 45 construction, in the combination and ag- groupment of components of the apparatus, in the method practised in connection therewith, and in certain novel details, all as will hereinafter be fully set forth and the 50 broad and specific scope of which will be indicated in the claims hereto appended.

In the accompanying drawings forming a part of this specification and in which like letters of reference indicate corresponding 55 parts, I have shown, by way of example, a form of structure well adapted to carry my

invention into effect; but, in thus illustrating a particular embodiment of my inventive-concept, I do not wish it to be understood that it is limited to the specific structure thus exhibited, because as a matter of fact, the invention is capable of being embodied in other forms and this without a departure from the spirit and underlying principles thereof.

In these drawings: Figure 1 is a view, principally diagrammatic and partly in horizontal section, of a dry-kiln constructed in accordance with my invention; Fig. 2 is a view in vertical section of a portion of the structure, including the heat-distributing flue, a drier-tunnel, and one of the radiators; Fig. 2^a is a fragmentary view, in vertical longitudinal section of a modified form of heat-conduit; Fig. 3 is a similar 75 view of another portion thereof, including the gas-intake, the mixing-chamber, the combustion-chamber, and the heat-flue; Fig. 4 is a fragmentary view, in vertical transverse section of still another portion, (including a drier-tunnel) and showing the relative position and arrangement of the radiators constituting components of the structure; Fig. 5 is also a fragmentary view, in horizontal section, illustrating a portion 80 of the mixing-chamber, and some of the radiators and air-flues; and Fig. 6 is a similar view, in vertical transverse section, illustrating a portion of the mixing-chamber, the gas-intake, and air-flues.

As the desideratum of the present invention is to simplify the general construction of ware-drying structure and at the same time provide for the effective utilization of the heat created from the combustion of 95 producer-gas and for efficient distribution of the heat-units to various portions of the structure, the principal components of that structure, as exemplified in the present embodiment, will now be described.

100 Referring to the drawings, it will be noted that the reference-character 1 designates, generally, a so-called tunnel-drier, for drying brick, tile, or other clayware; the same comprising end-doors 2, side-walls 3, and intermediate walls 4 dividing the building into a series of chambers or tunnels 5, 6 and 7. In each of the tunnels are arranged, in this instance, two sets of tracks 8 adapted to be traversed by ware-carrying cars or 110 trucks 9. At the extremities of these tracks, there may be full-gage tracks 10, 10, for

cars (not shown) upon or in which the completed product is loaded.

As an outstanding structure—but connected with the drier 1 proper—is a gas-producer 11, which may be of any approved type and of proper capacity. Communicating with the gas-producer 11 are mixing and combustion-chambers 12 and 12^a, with the former of which gas from the producer 11 is introduced, as by a gas-intake 13, and into which, also, air from an air-intake 14 is introduced. Extending between the drier-building 1 proper and the mixing-chamber 12 is an elongated heat-distributing flue 15 of relatively large dimension, preferably arched at the top, and having its wall 16 housed by an outside wall 17, there being a space 18 of proper size provided between the two walls for the passage of air from the intake 14 to the mixing-chamber.

As shown in Fig. 1, the air-intake 14 is disposed somewhat remotely from the mixing-chamber 12, and this is so that the intaken air may travel a considerable distance 25 and, thus, be warmed by the heat radiating through the wall 16. In this way, provision is made for heating the air before it actually enters the mixing-chamber 12.

The aforementioned mixing-chamber may 30 be of any appropriate form, but I have found to be entirely satisfactory one of the type illustrated in the drawings and particularly shown in Figs. 1, 5 and 6: It comprises a circumscribed area at one end of 35 the heat-flue 15, and in which a series of spaced chambered members 12^b are arranged, these opening into the combustion-chamber 12^a, as shown in Fig. 5, for instance. The producer-gas descends through the intake 13 (as shown in Fig. 6, for example) 40 and passes into the small chambers 19 and thence intermingles with the preheated air which passes into the spaces 20 between and at the sides of the gas-chambers.

45 In the combustion-chamber, the gas and air are ignited, and complete combustion is effected to furnish heat of any desired or required and predetermined intensity and volume. This heat then passes along the 50 main heat-flue 15—incidentally heating the air as the latter is moving from its intake toward the mixing-chamber—and enters upwardly-extending radiator-feeding passages 55 21 with which communicate a series of elongated heat-radiating conduits or radiators 22, there being any preferred number of 60 these—two being shown in the present instance—in each of the three radiator-chambers 23 subjacent the tunnels 5, 6 and 7, respectively.

In some embodiments of the invention, I 65 may elect to introduce the heat directly into the tunnels and utilize it there to dry the ware in lieu of radiating it from radiators. For this purpose, and as shown in Fig. 2^a,

conduits 22^a would be provided with apertures 22^b—preferably of predetermined and graduated size—in the upper portion of the conduits. The heat, as well as the moisture in the tunnels, would then escape, as through 70 a chimney 29. In either instance—whether the heat is radiated from the radiators or introduced directly into the tunnels, the ware is brought into the presence of heat developed from producer-gas. The intensity and volume of the heat may be predetermined and controlled in any appropriate manner, as by regulating the relative amounts of air and gas introduced into the mixing-chamber. In order to control the 80 passage of the heat-units through these radiators, suitable means are provided; and, in this instance, such means include dampers 24 operatively mounted on a shaft 25 which is common to two of them and with which 85 shaft is attached operating-levers 26.

Passing out of the opposite ends of the radiators, the spent gases of combustion enter a draft-flue 27, the necessary draft or suction therein being induced by any suitable means, as by an exhauster 28 coupled to the same.

The radiators being disposed in proper relation to the effective portions of the tunnels, the heat therein radiates from the same 95 into the respective tunnels and effects a drying of the ware on the cars or trucks therein. The moisture-laden air in the tunnels may be permitted to escape therefrom in any desired manner, as through the flue or chimney 29.

From the foregoing, it will be perceived that I have succeeded in devising a drier which is well adapted to achieve the several 105 objects and ends in view. The structure is simple and easily operated and controlled.

As many changes may be made in the foregoing structure and many apparently widely different embodiments of the invention can be made without departing from 110 the spirit thereof, it is intended that all matter contained in the foregoing description and illustrated in the accompanying drawings shall be interpreted as illustrative and not in a limiting sense. It is also to be 115 understood that the language used in the following claims is intended to cover all of the generic and specific features of the invention which, as a matter of language, might be said to fall therebetween.

What I claim is:

1. A drying apparatus comprising in combination a source of heat; a drying chamber; a mixing chamber connected with said source of heat; a combustion chamber associated with said mixing chamber; a heat distributing flue communicating with said combustion chamber; an air chamber associated with said heat distributing flue and communicating at one end with said mixing 125 130

chamber; an air inlet entering said air chamber at the other end thereof; and a flue connecting said drying chamber with said heat distributing chamber.

5 2. A drying apparatus comprising in combination a source of heat; a drying chamber; a mixing chamber connected with said source of heat; a combustion chamber associated with said mixing chamber; a heat distributing flue communicating with said combustion chamber; an air chamber associated with said heat distributing flue and communicating at one end with said mixing chamber; an air inlet entering said air chamber at the other end thereof; a radiation chamber associated with said drying chamber; and a flue connecting said radiation chamber with said heat distributing chamber.

10 3. A drying apparatus comprising in combination a source of heat; a drying chamber; a mixing chamber connected with said source of heat; a combustion chamber associated with said mixing chamber; a heat distributing flue communicating with said combustion chamber; an air chamber associated with said heat distributing flue and communicating at one end with said mixing chamber; an air inlet entering said air chamber at the other end thereof; a radiation chamber associated with said drying chamber; a flue connecting said radiation chamber with said heat distributing chamber; and a radiator disposed in said radiation chamber.

15 4. A drying apparatus comprising in combination a source of heat; a drying chamber; a mixing chamber connected with said source of heat; a combustion chamber associated with said mixing chamber; a heat distributing flue communicating with said combustion chamber; an air chamber associated with said heat distributing flue and communicating at one end with said mixing chamber; an air inlet entering said air chamber at the other end thereof; a radiation chamber disposed under said drying chamber; a flue connecting said radiation chamber and said heat distributing chamber; a plurality of radiators disposed in said radiation chamber; and damper instrumentality associated with said radiators.

20 5. A drying apparatus including in combination a drying chamber; a source of gas supply; a mixing chamber connected with said source of gas; a combustion chamber associated with said mixing chamber; a heat distributing flue connected with said combustion chamber; an air chamber disposed upon said heat distributing flue and connected at one end with said mixing chamber; an air intake at the other end of said air chamber; a radiator chamber communicating with said drying chamber; heat radiating instrumentality disposed therein; and

a radiator feeding flue connecting said heat distributing chamber and the heat radiating instrumentality.

6. A drying apparatus including in combination a drying chamber; a source of gas supply; a mixing chamber connected with said source of gas; a combustion chamber associated with said mixing chamber; a heat distributing flue connected with said combustion chamber; an air chamber disposed upon said heat distributing flue and connected at one end with said mixing chamber; an air intake at the other end of said air chamber; a radiator chamber communicating with said drying chamber; heat radiating instrumentality disposed therein; a radiator feeding flue connecting said heat distributing chamber and the heat radiating instrumentality; and damper instrumentality associated with said heat radiating instrumentality.

7. A drying apparatus including in combination a drying chamber; a source of gas supply; a mixing chamber connected with said source of gas; a combustion chamber associated with said mixing chamber; a heat distributing flue connected with said combustion chamber; an air chamber disposed upon said heat distributing flue and connected at one end with said mixing chamber; an air intake at the other end of said air chamber; a radiator chamber communicating with said drying chamber; heat radiating instrumentality disposed therein; a radiator feeding flue connecting said heat distributing chamber and the heat radiating instrumentality; and an exhaust flue connected with said heat radiating instrumentality.

8. A drying apparatus including in combination a drying chamber; a source of gas supply; a mixing chamber connected with said source of gas; a combustion chamber associated with said mixing chamber; a heat distributing flue connected with said combustion chamber; an air chamber disposed upon said heat distributing flue and connected at one end with said mixing chamber; an air intake at the other end of said air chamber; a radiator chamber communicating with said drying chamber; heat radiating instrumentality disposed therein; a radiator feeding flue connecting said heat distributing chamber and the heat radiating instrumentality; and a passage communicating directly with the atmosphere from the heat distributing chamber.

9. Clayware drying apparatus including a drying chamber, a source of producer-gas supply, a combustion chamber communicating therewith, and an elongated conduit connecting said drying and combustion chambers whereby heat may be conducted directly to the drying chamber and indirectly thereto by radiation.

- 4
10. A drying apparatus comprising in combination a drying chamber; a source of producer gas supply; a mixing and combustion chamber connected therewith; means for directing products of combustion from the mixing and combustion chamber directly to the drying chamber; and means for heating the drying chamber by radiation.
  11. A drying apparatus comprising in combination a drying chamber; a gas producer; a mixing chamber connected therewith; a combustion chamber associated with said mixing chamber; a heat distributing chamber; an air chamber disposed around said heat distributing chamber and connected at one end with said mixing chamber; an air intake disposed at the other end of said air chamber; a radiator feeding flue connected with said heat distributing chamber; a radiator chamber disposed beneath said drying chamber; a radiator connected at one end to said radiator feeding flue; a draft flue connected to the other end of the radiator; and an exhaust member connected with said draft flue.
  12. A drying apparatus comprising in com-

bination a gas producer; a mixing chamber connected therewith; a combustion chamber associated with said mixing chamber; a heat distributing flue connected with said combustion chamber; an air chamber partially surrounding said heat distributing flue and connected at one end with the mixing chamber; an air intake disposed at the other end of said air chamber; a series of radiator feeding flues connected at one end with the heat distributing chamber; a series of radiators connected at one end with said radiator feeding flues; a draft flue connected with the other end of the radiators; a plurality of radiation chambers inclosing said radiators intermediate their ends; a plurality of drying chambers disposed side by side over said radiating chambers; and means for closing communication between said radiators and said heat distributing chamber.

In testimony whereof I affix my signature in presence of two witnesses.

CHRISTOPHER G. GUIGNARD.
